WEFT DETECTING SYSTEM FOR SHIFTING
SHUTTLE BOX LOOMS

Richard Greenleaf Turner, Worcester, Mass.,
assignor to Crompton & Knowles Loom Works,
Worcester, Mass., a corporation of Massachusetts

Application May 7, 1935, Serial No. 20,141

16 Claims. (Cl. 139—233)

This invention relates to improvements in weft detecting mechanisms more particularly adaptable to shifting shuttle box looms and it is the general object of the invention to provide such a system which will detect the condition of weft in any shuttle just prior to picking thereof whether previously active or inactive.

Shifting shuttle box looms ordinarily employ at least one set or gang of cells at one end of the loom to house a plurality of weaving shuttles, and as ordinarily constructed such looms place one or another of the weaving shuttles in active picking position while the remaining shuttles are held inactive. When only two cells are used it is possible to detect into the top of the top cell and the bottom of the bottom cell, preferably by the movement of the shifting boxes. When the detectors are secured to the lay a very small pattern variation only is possible due to the fact that there is no means for detecting the condition of weft in the active shuttle and the latter must therefore be rendered inactive at frequent intervals to permit detection.

It is an important object of my present invention to add a third detector so placed that it cooperates with the active shuttle, thereby supplementing the detectors which are over and under the shifting boxes. It is possible to put the third detector either at the box end of the loom, or at the opposite end where a shuttle changer may be employed if the result of indication of weft exhaustion is to bring about a shuttle change, and I have chosen to show the auxiliary detector at the magazine end.

Heretofore I have proposed a loom wherein the single detector is employed at the magazine end with no detectors at the box end, the single detector cooperating with indication storing means which holds an indication given by any weaving shuttle when at the magazine end of the loom until that shuttle returns at a later pick, which may be several picks later. The indication storing means, however, involves selector mechanism and by the arrangement set forth hereinafter I am enabled to accomplish the detection of each shuttle just before it is to be active without the use of selecting mechanism and at the same time permit any shuttle to be active or inactive as long as required by the particular pattern being woven.

I illustrate my invention by means of electrical feelers which are controlled by some part such as the pattern mechanism which determines the sequence of box shifting. By this control the feeler of the inactive shuttle is rendered

incapable of giving an indication of exhaustion when in contact with a depleted idle shuttle until shortly before the shuttle is to be returned to action. The detector at the magazine end is also controlled by the pattern mechanism, being capable of detecting on the active shuttle on any detecting beat of the loom except that which immediately precedes a box shift. In this way I avoid double indication which might otherwise result should the inactive and active shuttles both be depleted at the same time.

It is a further important object of my present invention to distribute the wear on the weft incident to detection. The over and under feelers at the box end operate to cause engagement between the top of the weft in the upper shuttle and the bottom of the weft in the lower shuttle with their respective detecting surfaces, but when either of these shuttles is at the magazine end the third detector strikes the mass of weft in the front thereof. The result of this is that the detecting relations between the mass of weft and the detecting system occurs at different parts of the surface to be detected, and as a result any abrasion or wearing of the weft incident to the detecting operation is lessened due to distribution.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an elevation of the shuttle changing end of a loom made according to my present invention showing the single detector,

Fig. 2 is an elevation of the opposite end of the loom showing the shifting shuttle boxes in section and the over and under feelers which cooperate with them,

Fig. 3 is a detailed front elevation of the shifting shuttle boxes looking in the direction of arrow 3, Fig. 2,

Fig. 4 is a diagrammatic view of the circuits and controls for the boxes and circuits,

Fig. 5 is a diagrammatic view showing the sequence of operations, and

Fig. 6 is a detailed section on line 6—6 of Fig. 1.

In the accompanying drawings I have shown my invention applied to a two color shuttle changing loom of the type which has gone into general use and wherein shifting shuttle boxes are located at one side of the loom while a two-color reserve

shuttle magazine is located at the other side of the loom and is provided with control devices which coordinate the magazine with the active shuttle. The loom is also equipped with a so-called Knowles head which has provision for shifting the shuttle boxes at will, the sequence being that called for by any type of pattern which is desired to be woven with two shuttles. I do not wish, however, to be limited to a loom having the 10 particular head and boxes shown.

Referring particularly to Fig. 1, I have shown a loom frame 10 having a lay 11 which is rocked back and forth by a connector 12 driven by a top or crank shaft 13. The lay has a pair of shuttle 15 boxes the upper one of which indicated at 14 is normally opposite the rate to receive either of the weaving shuttles, while the lower box 15 is normally unoccupied but is raised at the time of shuttle change to receive the depleted shuttle arriving from the shifting box end of the loom. This shifting of the boxes 14 and 15 is accomplished through a box lifter rod 16 connected by a link 17 to a normally stationary lifter lever 18. The latter has a notched lug 19 to be entered by 20 a lifting dog 20 pivoted as at 21 to a regularly moving actuator lever 22. A solenoid 23 carried by the lever 22 moves the dog into lifting relation with respect to the notch 19 when excited so that as lever 22 rises it will elevate the lifter lever and 25 cause upward shifting to relate box 14 to the magazine M and place box 15 to receive the depleted shuttle.

The bottom shaft 24, turning once every two beats of the loom, carries a cam 25 which actuates 30 roll 26 on lever 22, the cam having low and high dwells 27 and 28, respectively, connected by inclines 29.

The magazine together with its color selector C of themselves form no part of my present invention and may be as set forth in my co-pending 40 application Serial No. 722,549 and are illustrated as means for controlling loom operation when one or another of the shuttles is depleted.

The opposite end of the loom illustrated in 45 Fig. 2 has a gang of shuttle boxes having upper and lower cells 30 and 31 respectively, adapted to receive a weaving shuttle S and S'. These cells are controlled as to vertical position by a box lifter rod 32 operatively related to a lifter chain 50 33 controlled by the head motion H. The latter is well understood and includes in its construction a vibrator lever 35, see Fig. 4, positioned vertically by a pattern chain P having high rolls 36 and sinkers 37 to give the vibrator lever one of 55 two positions. The vibrator lever carries a vibrator gear 42 which is given a partial rotation by one or the other of the upper and lower mutilated cylinder gears 38 or 39, respectively, depending upon the position of the vibrator lever. A vibrator connector 40 is pivoted to the gear at one end and at the other end to a box lever 41 the lower end of which is attached to the chain 33. The head operates in such a manner that when the vibrator lever is on a sinker the boxes are down 60 and when elevated by a riser or roll 36 the shifting boxes are raised. The matter thus far described is well understood and by the flexibility of patterns rendered possible by the chain P one or the other of the shuttle boxes 30 or 31 can remain active as long as desired while the other box is inactive, thereby providing the loom with 65 a call box motion.

The lay has secured thereto an electric feeler 70 45 above the boxes so positioned as to detect the 75 condition of weft in a shuttle in upper box 30 when

the latter is raised to inactive position, but incapable of detecting the upper shuttle when the latter is active. In a similar manner the lay has secured thereto a bottom or under electric feeler 5 46 to detect the condition of weft in the lower 10 shuttle box when the latter is inactive, but is equally capable of detecting the condition of the lower shuttle when the latter is active. These feelers may be secured in fixed relation to the lay and are rendered operative relatively to their 15 respective shuttles by shifting of the boxes. The over and under feelers which I employ may be substantially the same as those set forth in my aforesaid co-pending application.

At the magazine end I provide a third electric 15 weft detector 50 mounted to detect the condition of the active shuttle when the latter is at the magazine end of the loom. This detector is mounted on an arm 51 pivoted as at 52 to a bracket 53 secured to the magazine. A spring 105 20 holds the arm 51 yieldingly in rearward position against a stop 106. The upper box 30 has a cover 107 the forward part of which has a slot 113 to receive the rear end of a flexible tongue 110 mounted on the arm 51. Normally the cover advances with the lay below a tongue 110 but on a shuttle changing operation of the loom the box 30 and its cover 107 rises so that the cover 107 engages a shoulder 111 on the tongue 110 to move the latter, and therefore the arm 51 together with the detector 50 forwardly as the lay advances. In this way the detector at the weft replenishing end of the loom is moved out of the path of the incoming shuttle at the time of the shuttle changing operation. For further details of the mechanism for withdrawing the detector 50 reference may be had to my co-pending application Serial No. 667,464.

Fig. 4 indicates the control and electric circuits for my detecting system. A switch 60 for the over and under feeler has a contactor 61 which connects electrodes 62 and 63 constituting an upper pair when said cross bar is elevated due to raising of the vibrator lever 35, and connects lower electrodes 64 and 65 when cross bar 61 is down due to 45 lowering of the vibrator lever. The contactor is controlled by a rod 66 connected to an arm 67 moving with a second arm 68 operatively connected by link 69 to vibrator lever 35.

When the shifting shuttle boxes are in the position indicated in Fig. 4 with the lower shuttle S' temporarily inactive and depleted, the contactor 61 will be down to prevent closing of a contact through shuttle S' until just before a box shift is to occur, at which time the vibrator will rise 50 preparatory to the box shift and raise the contactor to the dotted position, whereupon current will flow in the following circuit: ground, wire 70, detector 46, shuttle S', wire 71, electrode 62, contactor 61, electrode 63, wire 72, solenoid 23, wire 60 73, source of electric power 74, and wire 75 back to the ground. This circuit remains closed between the raising of the vibrator lever and subsequent movement of box 31 away from feeler 46, long enough to energize the solenoid 23 and 65 move the dog into lifting relation with lever 18. Hooks 76 and 77 shown in Fig. 6 may be employed to hold the dog in the dotted position of said figure until lever 22 starts to rise as set forth more particularly in my co-pending application 70 Serial No. 747,358.

Upon becoming active shuttle S' is picked to the magazine side of the loom where it enters box 75 15, and it is to be understood that prior to the shift the other weaving shuttle S enters the top 75

box 30 and is moved toward its detector 45 which is controlled by the electrodes 64 and 65. The latter, however, are not connected because of the elevated position of the contactor 61 and therefore even though shuttle S be exhausted an indication cannot be given.

When the boxes are about to shift again to down position the indication for the shift will be given by a lowering of the vibrator lever to bring contactor 61 into low full line position prior to the box shift, whereupon if shuttle S be depleted current will flow in the following circuit: ground, wire 80, detector 45, shuttle S, wire 81, electrode 64, contactor 61, electrode 65, wire 82, solenoid 23, wire 73, source of electric power 74, and wire 75 back to the ground. Closing of this circuit will have the same effect as the closing of the previous circuit except that the magazine will operate to deliver a different shuttle, that is, one corresponding to shuttle S.

The matter thus far described may be similar to the circuits and structure shown in my aforementioned application Serial No. 722,549, and operates to detect only on a depleted inactive shuttle just 25 prior to the return of the shuttle to action.

Detector 50 is controlled so that it will detect on all beats of the loom when the previously traced circuits cannot be closed because of the position of either switch 60 or the active shuttle. 30 The third detector is controlled by an auxiliary vibrator lever 85 in head H which is positioned by an auxiliary chain 86 having high and low rolls 87 and 88, respectively. A link 89 connects the lever 85 with a circuit closer 90 capable of electrically connecting electrodes 91 and 92. The auxiliary chain is shown separately from chain P in Fig. 4, but in reality moves with the latter, and may indeed be part of it. Chain 86, like chain P, has a movement every beat of the loom, and is built so 35 that a high roll 87 which is at the end of a repeat on the main chain P will lift the circuit closer 90.

As shown in Fig. 4, the chain **P** for vibrator lever **35** has six high rolls **36** while the remainder are sinkers **37**. With the chain moving in the direction indicated by the arrow the last of the sinkers of the series at the right of the chain has arrived under the lever **35** and at the same time the high roll **87** is under the auxiliary vibrator lever **85**. In like manner when the last of the high rolls **36** arrives under vibrator lever **35**, another high roll **93** on the auxiliary chain will move under lever **85** and again raise the latter. Between high rolls on the auxiliary chain the vibrator lever **85** is down to permit current to flow between electrodes **91** and **92**.

When the feeler 50 detects a shuttle which is remaining active one of the low rolls 88 will be under lever 85, circuit closer 90 will be down as in dotted lines, and if exhaustion exists in a shuttle 60 at the magazine side under these conditions current will flow in the following circuit: ground, wire 95, detector 50, the depleted active shuttle, S as shown, wire 96, electrode 92, circuit closer 90, electrode 91, wire 97, solenoid 23, wire 73, battery 65 74, and wire 75 back to the ground. Current flowing in this circuit will energize the solenoid to move the dog with results similar to those already described.

Although the indication given by the detector 70 50 comes earlier in the cycle of loom operations than the indication at the box end, spring hooks 76 and 77 will nevertheless hold the dog until the shuttle changing period arrives. This and other relations will be described in connection with 75 Fig. 5, which shows diagrammatically the se-

quence of detecting operations for two successive picks or beats of the loom, and sets forth the sequence of operations relatively to cam 25 and bottom shaft 24 which makes one rotation in two beats of the loom.

In Fig. 5, where the sequence of operations is indicated graphically, FC, Top C, BC, and Bot. C represent, respectively the front center, top center, back center and bottom center positions of the lay.

Beginning at *a* on the dot and dash circle, it may be assumed that the lay is at front center and the active shuttle is to remain active and is being detected by feeler 50 at the magazine end. Under these conditions the circuit through the detector of the inactive shuttle will be broken by switch 60. If indication of exhaustion is given by feeler 50 the solenoid pulls the dog to changing position, where it is held by the hooks, the cam roll 26 being at the beginning of the low dwell 27 of cam 25. After picking at point *b* the shuttle travels toward the drop box end and boxes approximately at *d*, or bottom center, the feeler of the inactive shuttle remaining disconnected. At *e* lever 22 starts up on its regular motion and box 14 is up at *g*, where the shuttle is again picked. Transfer of the new shuttle is effected at *h* with the lay on back center, and box 15 remains up until the lay reaches bottom center, or *j*, to permit boxing of the depleted shuttle in box 15. The box 14 then drops to the shuttle race R, placing the new shuttle for picking at *b*. This operation requires a relatively long delay between indication by feeler 50 and magazine operation provided for by the full length of low dwell 27. 35

If it be assumed that the active shuttle at the magazine side is to be rendered inactive upon arrival at the shifting boxes, feeler 59 will be disconnected electrically by chain 86 at some point between *h* and *j* and no indication will be given, even though the shuttle be depleted. At some point between *c* and *d*, before the lay reaches bottom center with the shuttle traveling toward the boxes, the vibrator levers will change and the feeler corresponding to the inactive shuttle about to become active will be in circuit. If indication of exhaustion is given, the dog will rock to lifting position by action of the solenoid while the latter part of low dwell is still controlling lever 22 and before point *e* is reached. The subsequent shuttle changing operation will be as already described, but the interval between feeler indication and magazine operation will be less. When the loom next reaches a position between *c* and *d*, the switch 90 will be closed again to permit indication by feeler 59. It will be seen, therefore, that the cam is timed to operate correctly whichever feeler initiates the change.

By referring to Fig. 4 it will be seen that the feelers at the drop box end of the loom engage top and bottom surfaces of the bobbins being detected, but that when either shuttle is at the magazine end the detector 50 engages a different part of the mass of weft, namely the front, so that the wear incident to the physical contact between the detectors and the weft is distributed, thereby lessening likelihood of breakage when fine yarns such as silk and rayon are being woven.

From the foregoing it will be seen that I have provided a simple detecting system for a box loom wherein one detector is in control of the loom so long as the same shuttle remains in action, but that another part of the detecting sys- 75

tem comes into control and the first detector is disabled when there is to be a shift of the boxes. The timing of cam 25 is such that the indication can be given from either end of the loom 5 and for this reason the stationary detector, while described specifically herein as located at the magazine end, could with appropriate modifications be located at the shifting shuttle box end of the loom, this change involving no alteration 10 in the shuttle change mechanism. It will also be seen that the control for the auxiliary or third detector is attained through the use of an auxiliary chain built in such a way as to disconnect the detector, or disable the same, on the 15 last pick in which any one shuttle is to be active and just prior to a shifting of the boxes. It will further be seen that a shuttle changing loom supplying a plurality of types of reserve shuttles can be used in connection with a call box pattern 20 without the use of selective indication storing mechanism such as is customarily employed in looms of this type.

Having thus described my invention it will be seen that changes and modifications may be 25 made therein by those skilled in the art without departing from the spirit and scope of the invention and I do not wish to be limited to the details herein disclosed, but what I claim is:

1. In a loom having a lay and shifting shuttle 30 boxes at one end and a multicolor magazine at the other end, a pair of electric feelers supported on the lay, one over and the other under the shifting boxes, a single electric detector at the magazine end of the loom, means to determine 35 the sequence of movements of the shifting boxes, and means controlled by the first named means to render the single detector at the magazine end operative alternately with one or the other of the pair of detectors at the shifting box 40 end of the loom.

2. In a loom, a lay, shifting shuttle boxes on one end of the lay, an electric detector secured 45 to the lay to coact with an idle shuttle in the upper box when the boxes are raised, a second electric detector secured to the lay to coact with an idle shuttle in the lower box when the boxes 50 are lowered, a third electric detector at the end of the loom opposite the shifting boxes, loom changing mechanism to be controlled by any of the detectors, a pattern surface to determine the 55 sequence of movements of the shifting shuttle boxes, and controls between the pattern surface and the detectors to render the third detector operative to control the loom changing mechanism alternately with one or the other of the detectors secured to the lay.

3. In a loom, shifting shuttle boxes to render any one of a plurality of shuttles active for 60 periods greater than two successive picks, an electric weft detector for each shifting shuttle box, an electric weft detector at that side of the loom opposite the shifting boxes, a sequence control for the shifting boxes to determine the order in which the boxes are in active position, and 65 means operatively related to the sequence control to render the last named detector operative on all picks of a period except the last and to render operative the detector of a shuttle box in inactive position immediately prior to return of 70 said shuttle box to active position.

4. In a loom, shifting shuttle boxes to render active any one of a plurality of shuttles for a 75 period exceeding two picks, weft replenishing mechanism at the end of the loom opposite the 45 shifting boxes, a weft detector for each of the

shifting boxes, a deft detector at that end of the loom adjacent the replenishing mechanism, means to determine the sequence of movements of the shifting boxes, and connections between said means and the detectors effective to render the detector at the replenishing side of the loom operative during all picks except the last of a period of continued activity of any shuttle and to render one or the other of the detectors for the shuttle boxes operative during said last pick. 10

5. In a loom, shifting shuttle boxes at one end of the loom to render operative any one of a plurality of shuttles, a weft detector for each shuttle box, weft replenishing mechanism at the opposite end of the loom to be controlled by either 15 of said detectors, a weft detector at the magazine end of the loom also capable of controlling the weft replenishing mechanism, means to render said detector at the replenishing end of the loom capable of controlling said replenishing mechanism on those picks when an active shuttle 20 is to remain active and to render the detectors at the shifting shuttle box end of the loom capable of controlling the replenishing mechanism during those picks when there is a shift of the shuttle boxes. 25

6. In a loom, shifting shuttle boxes to render active any one of a plurality of shuttles for a 30 plurality of successive picks, a weft detector for each of said shifting shuttle boxes, a weft replenishing mechanism at the opposite end of the loom, a weft detector at the replenishing mechanism end of the loom, means by which each of said detectors is capable of controlling the replenishing mechanism, a pattern chain having 35 a section to determine which shuttle shall be active, and an auxiliary pattern surface carried by the chain, means controlled by the auxiliary pattern surface to control the detector at the replenishing end of the loom to render the latter 40 detector inoperative on the last of a sequence of picks during which a shuttle is active.

7. In a weft detecting system for a loom having two shuttle boxes which shift to render either 45 of two weaving shuttles active and inactive, weft detecting mechanism including two feelers, one for each shuttle, either feeler to indicate exhaustion of weft in the corresponding shuttle when inactive just prior to a shifting of the boxes which renders said inactive shuttle active and 50 the other of which is held in non-detecting mechanism with respect to the active shuttle, a second weft detecting mechanism to indicate exhaustion of weft in a shuttle which remains active, and means to bring about a change in the 55 operation of the loom when either detecting mechanism indicates exhaustion.

8. In a weft detecting system for a loom having two shuttle boxes which shift to render either 60 of two weaving shuttles active and inactive, a lay to support the shifting boxes, weft detecting mechanism supported by the lay and having two feelers, one for each shuttle, either feeler operative to indicate exhaustion of weft in an inactive shuttle about to become active while the other is out of position to detect the active shuttle, a second detecting mechanism to indicate exhaustion of weft in the active shuttle, and means to bring about a change in loom operation 65 controlled by both the said detecting mechanisms.

9. In a weft detecting system for a loom having two shuttle boxes which shift to render either of 75 two weaving shuttles active and inactive, a lay 75

to support the shifting shuttle boxes, detecting mechanism supported by the lay having two feelers, one for each shuttle, said feelers alternately effective to indicate exhaustion of weft in an inactive shuttle just prior to return to action of the inactive shuttle, a second detecting mechanism to indicate exhaustion of weft in the active shuttle, and means to bring about a change in loom operation controlled by both detector mechanisms.

10. In a weft detecting system for a loom having two shuttle boxes which shift to render either of two weaving shuttles active and inactive, a lay to support the shifting boxes, weft detecting mechanism secured to the lay including two feelers, one for each shifting box, said mechanism effective by shifting movement of the boxes to indicate exhaustion of weft in an inactive shuttle by the feeler corresponding thereto, just before the inactive shuttle returns to action, a second detector mechanism rendered effective by movement of the lay to indicate exhaustion of weft in an active shuttle, and means to bring about a change in loom operation controlled by both of said mechanisms.

11. In a weft detecting system for a loom having two shuttle boxes which shift to render either of two weaving shuttles active and inactive, weft detecting mechanism including two feelers, one for each shuttle box, each feeler effective to indicate exhaustion of weft when the corresponding shuttle box is in inactive position only and occupied by a depleted shuttle about to be returned to action by shifting of the shuttle boxes, a second detecting mechanism common to both shuttles and effective to indicate exhaustion of weft in either shuttle when active, and means to bring about a change in the operation of the loom controlled by both of said mechanisms.

12. In a shuttle having a lay operating with two shifting shuttle boxes to render either of two weaving shuttles active or inactive, two electric weft detectors secured to the lay, one above and the other below the shifting boxes, pattern mechanism to determine the sequence of movements of the shuttle boxes, an electro-magnetic loom controller, means effective upon indication of weft exhaustion in an inactive depleted shuttle and controlled by the pattern mechanism just prior to a shift of the boxes which returns the depleted shuttle to action to energize the electro-magnetic controller, an electric weft detector to cooperate with the active shuttle and capable of causing energization of the electro-magnetic controller during continued activity of a shuttle when the latter is depleted, and means moving in timed relation with the pattern mechanism to render the last named detector incapable of causing energization of the electro-magnetic controller during the last of a continuous series of picks during which any one shuttle is active.

13. In a loom, shifting shuttle boxes at one end thereof, a pair of weft detectors to cooperate with the shifting boxes, one detector for each box, a weft detector at the other end of the loom, weft replenishing mechanism to be controlled by each detector, pattern means to determine the sequence of movements of the shifting boxes, control means for the detector at said other side of the loom to render the last named detector operative to detect during certain periods and inoperative to detect during other periods, and means controlled by the pattern mechanism to render one or the other of said pair of de-

tectors at the shuttle box side of the loom operative to control the weft replenishing mechanism during the periods of inoperativeness of the detector at said other side of the loom.

14. In a loom, shifting shuttle boxes operating with a plurality of weaving shuttles, pattern mechanism capable of maintaining each shuttle box in active position for two or more successive beats of the loom, shuttle changing mechanism at the end of the loom opposite the shifting boxes, weft detecting mechanism at the shifting shuttle box end of the loom, a second weft detecting mechanism at the shuttle changing end of the loom, a controller for each weft detecting mechanism, each controller effective to render the corresponding weft detecting mechanism capable or incapable of indicating weft exhaustion, means controlled by the pattern mechanism and connected to the controller for the weft detecting mechanism at the shuttle changing end of the loom to maintain the last named weft detecting mechanism capable of indicating weft exhaustion when a weaving shuttle is to remain active for more than two successive beats of the loom, and means connected to the controller for the weft detecting mechanism at the shifting shuttle box end of the loom to render the latter weft detecting mechanism capable of indicating weft exhaustion when the weaving shuttle is to remain active for not more than two successive beats of the loom.

15. In a loom, a pair of shifting shuttle boxes at one end thereof to cooperate with two weaving shuttles, a weft detector for each of the shifting shuttle boxes, a main pattern surface to control the shifting movements of the shuttle boxes and capable of maintaining either shifting shuttle box in active position for a plurality of successive picks, means to mount the detectors so that each of the latter has detecting relation with the corresponding shuttle box when the latter is in inactive position only, control connections between the main pattern surface and the weft detectors to render the detector corresponding to an inactively placed shuttle box capable of giving indication of weft exhaustion only on a beat of the loom when the inactive shuttle box is to move to active position, a weft detector at the other end of the loom normally effective to indicate exhaustion of weft in the active shuttle, weft replenishing mechanism to be controlled by each of the detectors, an auxiliary pattern surface to control the detector at the weft replenishing side of the loom, connections between the auxiliary pattern surface and the last named weft detector to prevent the latter from giving an indication of weft exhaustion on a beat of the loom preceding a shift of the shuttle boxes caused by the main pattern surface, and means to drive the main and auxiliary pattern surfaces in synchronism to the end that indication of weft exhaustion can be given from but one end of the loom on any given beat thereof.

16. In a weft detecting system for a loom having two shuttle boxes which shift to render two weaving shuttles active and inactive, weft detecting mechanism to indicate exhaustion of weft in an inactive shuttle about to become active, a second weft detecting mechanism to indicate exhaustion of weft in an active shuttle, weft replenishing mechanism, connections between the latter and the weft detecting mechanisms to cause an operation of the weft replenishing mechanism when either weft detecting

mechanism indicates weft exhaustion, a main pattern surface to control the shifting movements of the shuttle boxes, an auxiliary pattern surface to control the second named weft detecting mechanism, means to cause the main and auxiliary pattern surfaces to move in synchronism, and control means for the weft detecting

mechanisms controlled by the main and auxiliary pattern surfaces to prevent the operation of the weft detecting mechanism of one end of the loom when the weft detecting mechanism at the other end of the loom is capable of indicating weft exhaustion.

RICHARD GREENLEAF TURNER.
